UNITED STATES PATENT OFFICE.

CARL PAUL GOERZ, OF GRUNEWALD, NEAR BERLIN, GERMANY.

DEVICE FOR SUCCESSIVELY EXPOSING SENSITIVE SHEETS.

No. 877,499.

Specification of Letters Patent.

Patented Jan. 28, 1908.

Application filed November 3, 1905, Serial No. 285,748.

To all whom it may concern:

Be it known that I, CARL PAUL GOERZ, manufacturer, a citizen of the German Empire, of 10 Bismarck-Allee, Grunewald, near 5 Berlin, Germany, have invented certain new and useful Improvements in a Device for Successively Exposing Sensitive Sheets, of which the following is a specification.

My invention relates to a method for successively exposing sensitive sheets (plates, 10 films, etc.) in a suitable chamber by pulling the exposed sheets one after the other out of the exposing chamber into a collecting chamber.

15 The invention does away with the necessity of providing a special chamber for gathering the exposed sheets by using the light tight envelop in which the sheets are inclosed before same are inserted into the exposing chamber at the same time as collecting chamber for the sheets after exposure.

Therefore the invention comprises an exposing chamber and a package containing sensitive sheets said package having a light 20 tight envelop adapted to be shifted off the sheets contained therein.

Particulars of the invention are explained hereafter with reference to the drawings forming part of this specification.

30 In the drawings Figures 1 to 6 relate to changing of so called "films" and Figs. 7 to 9 to the changing of plates. Fig. 1 is a representation of an exposing chamber adapted to inclose a pile of films. Fig. 2 shows a film with end extensions forming 35 pulling strips. Fig. 3 shows a package with films. Fig. 4 shows the exposing chamber of Fig. 1 filled with the package of Fig. 3. Fig. 5 is a longitudinal section through the

40 film package represented in Fig. 3. Fig. 6 is a longitudinal section through the filled exposing chamber the exposing chamber being shown closed and the light tight envelop or cover pulled from the films and out of the 45 exposing chamber. Fig. 7 shows a package with plates. Fig. 8 is a section through an exposing chamber filled with the package of Fig. 7. Fig. 9 is a section through the filled exposing chamber the envelop or cover of 50 the package being pulled from the plates and out of the exposing chamber. Fig. 10 shows a longitudinal section through a modification in which the light-tight envelop contain-

ing the films is connected to the exposing chamber from the outside without being at 55 first inserted into said chamber.

Referring more particularly to Figs. 1 to 6 of the drawings: The exposing or film changing chamber shown in Fig. 1 has a cover *a* jointed thereto said cover being provided at both ends with strips *b*, *c* of velvet or similar material. Opposite the strip *c* of the cover *a* is a strip *d* fastened to the exposing chamber, so that the strips *c*, *d* are pressed together on closing the cover *a*. At 65 the end of the exposing chamber which is opposite the end carrying the strip *d* the chamber is provided with a mouth piece *e* having a free passage. The mouth piece *e* may be formed from cloth or other foldable 70 material and provided at the end turned to the outside of the exposing chamber with a rigid frame. The film represented in Fig. 2 is designated *f*. The film is provided at both ends with unsensitive extensions forming 75 pulling strips *g*, *h*. The light tight cover inclosing a pile of films *f* is designated *i*. The cover *i* is provided with side extensions *i'*. The cover *i* is shiftable on the pile of films and for this purpose is provided at both ends 80 with ribs or strips *k*, *k* and *l*, *l*, respectively of velvet or similar material adapted to form passages for the pulling strips and the films and to make a light tight contact with opposite surfaces of the pile. The light tight 85 cover *i* of the film package is provided with a flap *m*, which may be grasped in order to shift the envelop *i* off the films.

The use and operation of the devices described is as follows: Assuming that the exposing chamber has been opened as is shown in Fig. 1 of the drawing, then the film package shown in Fig. 3 is inserted in such a manner that the flap *m* and the pulling strips *h* pass through the channel of the mouth piece *e*. Now the cover *a* of the exposing chamber is closed with the effect that the flaps *g* are squeezed between the ribs *e*, *d* of the exposing chamber; at the same time the rib *b* is pressed against the side wall of the 100 mouth piece *e* so that the channel of such mouth piece is tightly closed. Now one grasps the flap *m* and at the same time the flaps *g* and begins to pull. When doing so the light tight cover *i* is shifted off the film 105 pile and passes through the channel of the

mouth piece *c*. The movement of the cover *i* is limited by engagement of the side extensions *i'* of the envelop *i* with the mouth piece *c*. Now the cover *i* has the position shown in Fig. 6 and jams the strips *h* between its ribs *l*. The cover *i* may be turned over so as to contact, with the cover of the exposing chamber this being enabled by the foldable nature of the material forming the mouth piece *c*. If now a film has been exposed and if it is desired to take it out of the exposing chamber and to transport it into the collecting chamber which is formed by the cover *i*, then the operator grasps the pulling strip or flap *h* of said film and pulls the film between the ribs *l* of the cover *i* into the hollow of the cover. This procedure is repeated as often as a film has been exposed within the exposing chamber. If the films in the exposing chamber, which originally in unexposed condition were in the cover *i*, are all exposed and transported back into the cover *i* then the apparatus is brought into a dark room and the cover *i* is loosened from the exposing chamber and the films are taken out for development.

If it is desired to develop exposed films before the whole stock within the exposing chamber is exhausted this can also be done. In this instance the apparatus must also be brought into a dark room and the exposing chamber must be opened. In this instance it is necessary to lift the sensitive films within the exposing chamber and to pull the exposed films, by grasping the flaps *g* back into the exposing chamber and to take them out. The unexposed films may remain within the exposing chamber and also the cover *i* may remain, connected with the exposing chamber for further use as collecting chamber for the unexposed films which are still within the exposing chamber.

Referring now particularly to Figs. 7 to 9 it is to be stated that the devices shown in these figures differ from the described devices only in so far that means are provided for allowing the light tight cover of the package to be shifted from the pile of sensitive plates which is thicker than the pile of films. In this instance simple ribs like the ribs *k* in Fig. 5 would not be sufficient to secure at the same time light tight jamming of the flaps *g* and to allow the passage of the pile of plates between such ribs. Now the package of plates illustrated in Figs. 7 to 9 has a light tight cover which is provided with a bag-like end-piece *n* at that end of the cover which is opposite the end which has the pulling flap connected thereto. This bag-like end piece consists of foldable material such as paper and has a flap *p* adapted to close the end of the bag by being pasted to the side face of the bag as is clearly shown in Fig. 7 of the drawing. *q* is a thread or wire which may be interposed between the flap *p* and the side

face of the bag *n* to which said flap is pasted. The thread or wire enables a cutting through of the flap by exercising a pull on the end of said thread resulting in an opening of the flap. Such opening of the flap *p* is effected only when the package has been inserted into the exposing chamber in the same manner as formerly described in connection with the package for films. When the flap *p* pasted on the side face of the bag *n* has been cut through by the wire *q*, the bag may be opened as shown in Fig. 8, allowing the plates contained within the package to pass through the open end of the bag, so that the envelop *i* may be drawn outside the exposing chamber, whereas the plates remain within the exposing chamber as shown in Fig. 9.

The exposing chamber is provided with ribs or strips *r*, *s* of velvet or similar material adapted to in a light excluding manner jam the plate flaps between them, so that after the insertion of the package into the exposing chamber the opening of the flap by cutting it through with the thread *q* may be effected without danger of entering light into the exposing chamber through the open bag. At the end opposite the strips *r*, *s* the exposing chamber is provided with an extension *t* forming a channel in free connection with the interior of the exposing chamber and provided with a mouth piece *u* forming a light tight bearing for the envelop *i*. After the bag *n* has been opened as described the cover *i* may be shifted from the plates and pulled out of the exposing chamber and the plates may be transported into the hollow of such cover just in the same manner as formerly described with relation to films.

In the foregoing description it has been assumed that the package with sensitized sheets is inserted into the exposing chamber and that then the light tight cover is pulled from the films or plates so that the same remain within the exposing chamber whereas the cover is transported out of the exposing chamber however remaining in light tight connection with same. The process itself of successively exposing the sensitized sheets originally contained within the package only requires a collecting chamber outside the exposing chamber and in light tight connection with same and sensitized sheets within the exposing chamber and adapted to be pulled into the collecting chamber. Therefore the manipulation above described may be modified in such a manner that instead of inserting the package into the exposing chamber and pulling the light tight cover off the sensitized sheets the package with the sensitized sheets may be light-tightly joined with the exposing chamber from the outside and the sensitized sheets pulled from the light tight cover into the exposing chamber. In this instance the pulling strips of the sensitized sheets on the one

end of each sheet must be sufficiently long to penetrate from outside the one end of the length of the exposing chamber to outside the other end of said chamber whereas the 5 strips on the other end of each sheet must be sufficiently long to penetrate from outside the one end of the length of the light-tight cover of the package to outside the other end of said package as is clearly shown 10 in Fig. 10 of the drawings. In this modification of the procedure it is necessary to tear off the pulling strip of each sensitized sheet at the free end of the exposing chamber after exposing before drawing said exposed sheet 15 into the light tight cover forming the collecting chamber in order to expose the next sensitized sheet because otherwise said pulling strip would form a cover for the sensitized sheet to be exposed. The devices above 20 described are however substantially independent from the several modifications of the procedure which may be adopted.

I have shown and described the best means now known to me of embodying my 25 invention without intending to limit myself to the exact constructions so described and shown except as the scope of the claims demands.

Having now described my invention what 30 I claim and desire to secure by Letters Patent is:—

1. A device for successively exposing sensitive sheets comprising an exposing chamber having an open mouth and a package comprising sensitive sheets and an inclosing light-tight envelop, said envelop being adapted to be shifted with relation to the sensitive sheets contained therein in such a manner that one element of the package passes through the 40 open mouth of the exposing chamber.

2. A device for successively exposing sensitive sheets comprising an exposing chamber having an open mouth and a package of sensitive sheets contained in a light-tight envelop, said package to be connected with the exposing chamber, the sensitive sheets being provided at opposite ends outside the envelop with unsensitive extensions and the elements of the package being adapted to be 45 shifted with relation to each other in such a manner, that one element passes through the open mouth of the exposing chamber.

3. A device for successively exposing sensitive sheets comprising an exposing chamber 55 having an open mouth and a package comprising sensitive sheets and an inclosing light-tight envelop forming one single compartment, each sensitive sheet being provided at least at one end with an extension extending outside the envelop, said envelop being adapted to be shifted with relation to the sensitive sheets contained therein in such a manner that one element of the package passes through the open mouth of the exposing 60 chamber.

4. As a new article of manufacture, a package comprising one or more sensitive elements having tabs, and a light-tight envelop slidably mounted thereon.

5. As a new article of manufacture, a package comprising one or more sensitive elements each having a long tab on one end and a short tab on the other end, and a light-tight envelop normally surrounding the sensitive elements and adapted to be moved on to the 75 long tab.

6. As a new article of manufacture, a package comprising one or more sensitive elements having tabs and a light-tight envelop slidably mounted on the sensitive elements 80 and having at least one tab.

7. As a new article of manufacture, a package comprising one or more sensitive elements having tabs and a light-tight envelop slidably mounted on the sensitive elements, 85 said light-tight envelop being provided at least at one end with light excluding members tightly inclosing the said sensitive elements with tabs.

8. As a new article of manufacture, a package comprising one or more sensitive elements having tabs and a light-tight envelop slidably mounted on the sensitive elements, said light-tight envelop being provided at least at one end with a pair of ribs opposite to 95 each other, the ribs forming a pair tightly inclosing the said sensitive elements with tabs between them.

9. As a new article of manufacture, a package comprising one or more sensitive elements having tabs and a light-tight envelop 100 slidably mounted on the sensitive elements, said light-tight envelop being provided at one end with a pair of ribs tightly inclosing the tabs of the sensitive elements between 105 them in a light excluding manner and at the opposite end with a baglike part adapted to form a light-tight closure of the envelop.

10. The combination of an exposing chamber, a package of sensitive elements removably located therein and having tabs projecting from the opposite ends thereof, and a light tight envelop surrounding the sensitive elements and adapted to be partially drawn out of said exposing chamber, for substantially 110 the purposes set forth.

11. The combination of an exposing chamber, a package of sensitive elements removably located therein and having long tabs projecting from one end of the chamber and short tabs projecting from the opposite end thereof, and a light tight envelop surrounding the sensitive elements and adapted to be partially drawn out of said chamber so as to cover the long tabs, for substantially the purposes set forth.

12. The combination of an exposing chamber, having openings in its opposite ends, a package of sensitive elements located in said chamber and having tabs projecting through 130

the end openings thereof, and a light tight envelop surrounding said sensitive elements and having a tab projecting through one of the end openings of said chamber, said envelop being adapted to be partially drawn out through one end opening of the chamber, for substantially the purposes set forth.

In testimony whereof I have signed this specification in the presence of two subscribing witnesses.

CARL PAUL GOERZ.
